CLAIM

The ornamental design for a blender as shown and described.

DESCRIPTION

FIG. 1 is a first perspective view of a blender, showing my new design;

FIG. 2 is a second perspective view of the blender, shown with the container element removed;

FIG. 3 is a front elevation view thereof;

FIG. 4 is a rear elevation view thereof;

FIG. 5 is a left side elevation view thereof;

FIG. 6 is a right-side elevation view thereof;

FIG. 7 is a top view thereof; and,

FIG. 8 is a bottom view thereof.

The broken lines depict portions of the blender that form no part of the claimed design.

1 Claim, 5 Drawing Sheets
